UNITED STATES PATENT OFFICE.

JOHN ERICSSON, OF NEW YORK, N. Y., ASSIGNOR OF ONE-HALF TO CORNELIUS H. DELAMATER AND G. H. ROBINSON, OF SAME PLACE.

STEAM-ENGINE.

SPECIFICATION forming part of Letters Patent No. 247,813, dated October 4, 1881.

Application filed July 1, 1881. (No model.)

To all whom it may concern:

Be it known that I, JOHN ERICSSON, of the city, county, and State of New York, have invented certain new and useful Improvements 5 in Steam-Engines, of which the following is a specification, reference being had to the accompanying drawings.

The principal object of my invention is to provide a reciprocating steam-engine which is capable of running at a very much higher velocity than the reciprocating steam-engines in common use, and which is thereby better adapted 10 as a motor for dynamo-electric machines and other machines requiring to be driven at high speed, and for the driving of which it is desirable to dispense, as far as practicable, with driving-belts and gearing. In an engine running at so high a velocity it is desirable 15 to obtain the greatest possible stability in proportion to its weight and the greatest possible strength in the connections of the parts; to reduce as far as practicable the number of parts to be lubricated, and to provide, as far as possible, for the automatic lubrication of 20 such parts as have to be lubricated. These ends I accomplish by the construction and arrangement of parts embodied in the engine illustrated in the accompanying drawings, in which—

30 Figure 1 is a vertical section of a steam-engine with my improvements, taken in a plane parallel with the crank-shaft. Fig. 2 is a transverse section of two disks forming parts of the joint between the main connecting-rod and piston. Fig. 3 is a face view of one of the said disks. Fig. 4 is a vertical central section of the engine, taken at right angles to Fig. 1. Fig. 5 is a side view of the valve-stem, valve-rod, and their connections. Fig. 5* is a side view, on 35 a larger scale, of the upper part of the valve-connecting rod. Fig. 6 is a plan of the standard and crank. Fig. 7 is a horizontal section of the base and steam-cylinder.

B is the base of the engine, made hollow in 45 the form of an inverted box, of upright cylindrical or other suitable form, of a depth somewhat greater than the length of the cylinder, and having the sides and bottom of the cylinder C cast with it in the form of a pot depend- 50 ent from its upper part. The base and cylin-

der being thus constructed, give great stability to the engine, and the base forms an air-jacket to the cylinder for retaining the heat therein. On the base B is erected an upright hollow column or standard, D, on the top of which 55 are the bearings H H for the journals of the main or crank shaft E.

F is the piston, constructed or provided with a hollow central rod or trunk, F', working through a stuffing-box, C², in the cylinder-cover C'.

G is the main connecting-rod, connected with the piston by a transverse pin-joint at a in the manner to be presently described. This rod is represented as eighteen times the length of 65 the crank of the main shaft, and its vibration is, therefore, very little more than three degrees of a circle, so that there is a very slight oscillation of the joint-pin a, and very little side thrust, so that the piston may be guided 70 by the trunk or hollow rod F' and stuffing-box C² without the necessity of cross-head or slides and without the necessity of making the said trunk or rod of large size. The exterior of 75 said trunk or rod is kept lubricated by oil or tallow contained in the small cup b, formed in the gland of the stuffing-box C². The pin a is rigidly secured in the lower end of the connecting-rod by being properly fitted to a hole bored through the lower part of the latter, and inserted thereinto while the latter is hot, and permitting the latter to shrink upon it by cooling; and the pin projects from the opposite sides of 80 the rod in the form of cylindrical journals. The said pin is connected with the piston within the latter by means of two disks, c c, which are fitted together, as shown in Fig. 2, to form journal-boxes for the said pin, and are secured in the piston by a follower, d, screwed into the bottom of the piston. To enable it to receive 85 these disks and follower the piston is bored from its under side, as shown in Fig. 1, to a shoulder, e, and has a screw-thread cut around the interior of the mouth of this to receive the screw-thread on the exterior of the follower. 90 The said disks are solid, except that each has formed within it one-half of each of the two bearings f f for the pin a, and a central slot or opening, g, for the portion of the 95 connecting-rod which receives the said pin. 100

They are secured firmly against the shoulder *e* by the follower *d*. Above the shoulder *e* there is provided in the piston a cavity, *h*, which communicates with the interior of the trunk or hollow piston-rod, and below the disks *cc* there is a cavity, *i*, in the follower *d*, and there is, therefore, formed within the piston and piston rod or trunk a well or reservoir, into which oil or tallow is introduced through the upper end 10 of the piston rod or trunk, and which may be kept supplied with oil or melted tallow, with which the lower end of the connecting-rod and pin *a* are always surrounded, so that the whole of the pin-joint can never fail to be properly lubricated.

The crank-arms *E' E'* of the main shaft are represented as having fitted over them disks *E² E²*, which are concentric to their shaft, and which are secured to them by set-screws *ll*. 20 These disks serve as counter-balances to the arms and crank-wrist, and also as fly-wheels.

For the purpose of providing for the oiling of the crank-wrist and the box *m m'*, which connects it with the connecting-rod *G*, there is cast in the cap *m'* of the said box a large oil-cup, *m²*, in the center of which is a tube, *m³*, which is open at the top, and which forms the only communication between the oil-cup and the wrist-bearing. In the lower part of this tube is inserted snugly a plug, *n*, formed by rolling up somewhat tightly a strip of muslin, canvas, or other woven fibrous material. This plug is secured in the tube, so that its lower end touches the wrist by means of a small pin, *n'*, inserted transversely through holes in the tube above the said plug.

The cup *m²* is to be supplied with oil through an opening in its top, which is fitted with a tight screw-cap, *m⁴*. When the engine is in 40 operation the oil is thrown by the vibration of the rod from the cup *m²* into the upper part of the tube *m³*, down which it flows to the fibrous plug *n*, through which it passes to the wrist in quantity regulated by the tightness 45 with which the said plug is rolled. By this plug the supply of oil can be more perfectly regulated without waste than is possible with a wick.

I is the slide-valve for the induction and 50 eduction of steam. The seat *h'* of this valve, the cylinder-ports *i' i'*, and the exhaust-cove *k* are represented as constructed in the same casting with the cylinder and the base *B*. The valve consists simply of a flat plate with an 55 opening, *o*, through it of proper shape for the exhaust-space, and is straddled, as shown in Fig. 7, by a saddle, *J*, which is also represented in Fig. 1. This saddle fits the back and sides of the valve, and also fits between the sides of 60 the valve-chest *K*, and forms a guide to the valve. It is held up steam-tight to the back of the valve by means of light springs *p p*, which are secured to its own back and bear against the inside of the back of the valve-chest *K*, and it is held against longitudinal movement between set-screws *q q*, screwing 65 through the ends of the chest.

The valve is operated by a crank, *L*, on one end of the main shaft and a connecting-rod, *M*, which is connected with the valve-stem *I'* in 70 a peculiar way, illustrated in Fig. 1 by a pin-joint composed of a piston, *N*, and a joint-pin, *r*, the said piston working in a stationary cylinder, *O*, which is firmly secured in an upright position to the column *D* or framing of the 75 engine, and which serves both as a guide to the valve-stem and an oil-reservoir for oiling the joint. The cylinder *O* is bored throughout of uniform size. The piston is formed upon or rigidly secured to the head of the valve-stem *I'*. Its head or principal portion, which receives the pin *r*, is represented as made in the same piece with the stem *I'*, on which, below the said head, there is a screw-thread for the 80 reception of a nut, *s*, by which a leather cup-packing, *t*, fitted to the cylinder *O*, is secured to the said head. The piston *N* is slotted from the top for the reception of the lower end of the connecting-rod *M*, which and the piston have holes bored transversely through them 85 for the reception of the joint-pin *r*. The portion of the cylinder *O* above the piston *N* forms a reservoir, which is kept copiously supplied with oil. This oil cannot pass the cup-packing of the piston, but it keeps the pin *r* and all the surfaces of the joint between the valve-stem and rod immersed, and therefore thoroughly lubricated, while at the same time it lubricates the surfaces of the cylinder and piston, which serve as guides to the valve-stem. 90

The connection of the upper end of the valve-connecting rod *M* with the wrist of the crank *L* is made by a slotted head, *L'*, which is made separate from the rod, and the lower part of which is bored for the passage of the rod, the latter having a screw-thread, *u*, on its upper part, which enters the slot *v* of the yoke, and a screw-thread, *u'*, lower down below the head *L'*, the said screw-threads being fitted with nuts *x x'*, and between which the bottom part of the head is clamped and secured to the rod. 100

The upper half, *w*, of the crank-wrist box is represented as made in the head itself, and the lower part of a separate brass, *w'*, which is fitted to the slot *v*, and which is set up to the 115 wrist by a nut, *y*, screwed onto the thread of the rod, a jam-nut, *y'*, being also fitted to the said thread below *y'*, to secure the adjustment of the box to the wrist. The upper part of the head *L'* is represented as furnished with an oil-cup having a central tube fitted with a fibrous plug precisely as is the main crank-wrist box *m m'*, as hereinbefore described.

The above-described method of constructing the connection between the valve-connecting rod and its operating-crank provides conveniently for screwing up or adjusting the lower brass, *w'*, as required, while dispensing with straps and keys, which, owing to the very high velocity of the engine, would be apt to become 120 loose.

I do not here claim the construction of the connection between the valve-stem and the valve-rod as illustrated in Figs. 5 and 5* of

the accompanying drawings, as such will form the subject matter of a separate application for Letters Patent.

What I claim as my invention is—

- 5 1. In a reciprocating engine, the combination, with the piston constructed with a central bore in its under portion and provided with an upright hollow rod or trunk in communication with the bore in the piston to form a receptacle for a lubricant, of the connecting-rod provided at its lower end with a pin projecting from opposite sides of the rod in the form of cylindrical journals, the two loose disks arranged centrally in the piston-body and provided with slots and semi-cylindrical bearings for the reception of the connecting-rod and its journals, and the follower fitted to a screw-

thread in the piston and capable of rotating independent of the lower disk, for holding and adjusting the parts in position, all substantially as described.

2. A connection between the valve-stem and its connecting-rod of a steam-engine and a guide for the said stem, consisting of the combination of a packed piston formed or secured on the valve-stem, a joint-pin connecting the said rod with the said piston, and a stationary cylinder in which the said piston works, and which forms an oil-reservoir, substantially as herein described.
